OF NEW YORK, N. Y., A CORPORATION OF NEW JERSEY.

FOOTBALL HELMET.

Application filed March 9, 1927. Serial No. 173,865.

The present invention relates to helmets, particularly those adapted for use in playing football, and has for an object the provision of a helmet, the dome of which is constructed 5 in such a manner that it will protect the head of the player against shocks resulting from excessive blows.

In the manufacture of existing forms of helmets the crown portion has been formed 10 of a plurality of segments of leather secured in a manner requiring a great amount of time and labor. After the pieces have been cut in the desired rough shape, adjacent pieces are laid with the outer sides together and stitched 15 along the one side. The rough crown portion is then soaked in water for twenty-four hours or more until it has softened sufficiently. The segments are then opened out and placed with the flesh side of the leather against a suitable 20 form. In opening out the segments in this manner, the adjacent pieces will be turned away from each other as are adjacent leaves of a book when opened, and it is necessary that the leather be soft in order that the 25 stitches will not be broken. After placing the piece upon the form it is hammered with a mallet along the seams to make a smooth and flat butt joint. In this process, a severe strain is placed upon the seams and, even 30 with the exercise of great care, it is extremely difficult to prevent the breaking of the stitches in many instances. In order to give added strength to this joint and impart greater rigidity to the crown, a strip is sewed over 35 the joint and along the seam.

Seams of the above character are highly flexible and even with the addition of the protective strip, the crown portion is insufficiently rigid to protect the wearer's head 40 against the blows received during play.

An object of the present invention is to provide a helmet constructed along different lines wherein leather of a sufficiently rigid character is used and formed into a helmet.

An object of this invention is to provide a helmet of the above character to protect the head from the most severe blows received thereby while having in mind that it must not present an outer surface of too hard a 50 nature so that injury to other players might result.

The particular construction of the crown whereby non-yielding qualities are imparted thereto includes the assembling of non-

yielding front, rear and side sections and 55 sewing them together by means of lap seams whereby a much greater strength is imparted to the crown than would be had with other forms of seams. In the final forming and shaping of the helmet, this construction results as a stronger and more rigid construction. In this manner the hardness is imparted to the crown and the desirable features noted above are accomplished. 60

Restating the object of the present invention, it may be said to provide a helmet made of two or more crown sections of relatively non-yielding character which are assembled in a manner to impart to the entire crown a uniform strength at all points, and in this 70 manner cause the shape and non-yielding character of the crown portion to be preserved indefinitely.

In order to set forth the invention more clearly, reference will now be had to the accompanying drawings forming a part hereof, wherein:

Figure 1 is a perspective view of the helmet looking from the front and showing the crown construction above referred to. 80

Figure 2 is a section taken on line 2-2 of Figure 1 and looking in the direction of the arrows.

Figure 3 shows a front elevation of the helmet with portions thereof broken away. 85

In the drawings, *a* represents the crown piece of a helmet of the proposed design having side and ear extensions *b*. This lower portion of the helmet may be made in accordance with well known practice and its specific form plays no part in the present invention. The crown piece *a* may be secured to the lower portion by straps *c*, or other suitable means which will permit of some relative movement between the two, and is composed of side sections *a'* and end sections *a''*. These sections are formed of stiff and relatively non-yielding leather and are sewed together by lap seams *d*. The edges of the sections to be stitched together are preferably skived, as shown in Fig. 2, so as to render the top of the helmet as even as possible. Obviously, the seams may be riveted, glued, or secured in any desired manner and it will be seen that the resulting article consists of a crown portion, the shape of which will be preserved indefinitely by reason of its uniform strength at all points, since the places at which old

structures were weakened are made equally as strong if not stronger, than the rest of the crown portion. It is essential to the rigid construction and utility of the crown section 5 that these seams be lapped and, accordingly, this forms an important part of the helmet.

At the apex of the crown a top piece *e* is applied to finish off the converging points of the sections *a*¹ and *a*².

10 On the underside of the crown piece, strips of fabric *f* are sewed to the lower portion *b* at spaced points around the interior circumference thereof. These straps intersect beneath the apex of the crown and are sewed 15 together in the usual manner. It is desirable that the straps *f* be sewed to the lower portion *b* together with the straps *c* so that this may be done in one operation.

The old methods of manufacturing helmets 20 required that the leather be capable of manipulation and thus restricted the finished article to a relatively flexible helmet. The helmet described herein is of an extremely non-yielding character, although constructed 25 so that the portions thereof which come in

contact with other players will not injure them.

What I claim is:

In a football helmet, a relatively non-yielding crown portion formed of an outer 30 material of a plurality of sections of relatively stiff material having skived edges joined together by means of lap seams, whereby the outside of the crown may present a continuous smooth surface and whereby the 35 use of outside reinforcing strips is eliminated, padding within the crown portion, a separate relatively flexible lower portion, the outer surface of which is in the same general plane with that of the crown portion, padding within the lower portion, and means between the outer material and the padding of the crown and lower portions and forming the sole connecting means therebetween to connect the crown portion and the lower portion, 40 said means permitting a degree of relative movement between the two.

This specification signed this 5th day of March A. D. 1927.

ROBERT T. MULLINS.
